UNITED STATES PATENT OFFICE.

SAMUEL A. LATIMER, OF BANGS, TEXAS, ASSIGNOR OF ONE-HALF TO
JOSEPH KRISCHKE, JR., OF BROWNWOOD, TEXAS.

BUILDING-BLOCK MACHINE.

No. 831,230.

Specification of Letters Patent.

Patented Sept. 18, 1906.

Application filed October 7, 1905. Serial No. 281,808.

To all whom it may concern:

Be it known that I, SAMUEL A. LATIMER, a citizen of the United States, residing at Bangs, in the county of Brown and State of Texas, have invented new and useful Improvements in Building-Block Machines, of which the following is a specification.

This invention relates to building-block machines of the type employed for molding concrete or other artificial-stone blocks, and has for its objects to produce a comparatively simple inexpensive device of this character in which the walls of the molds will be moved to open position and the cores automatically withdrawn from the molds, one wherein the operating mechanism will be locked against movement at the completion of the mold opening and closing operations, and one wherein the parts may be readily adjusted to provide for the formation of blocks of varying sizes.

With these and other objects in view the invention comprises the novel features of construction and combination of parts more fully hereinafter described.

In the accompanying drawings, Figure 1 is a perspective view of a machine embodying the invention and showing the parts of the mold in casting position. Fig. 2 is a similar view showing the mold open to permit removal of the blocks. Fig. 3 is a top plan view of the machine with the mold in place. Fig. 4 is a similar view with the mold removed. Fig. 5 is a vertical longitudinal section taken centrally through one of the mold compartments. Fig. 6 is a vertical transverse section taken on the line 6-6 of Fig. 3. Fig. 7 is a detail perspective view of one of the hinge members. Fig. 8 is a similar view of one of the crank-arms and a portion of the adjacent connecting-rod. Fig. 9 is a detail perspective view showing the manner of connecting the bars of the core-frame.

Referring to the drawings, it will be seen that the frame of the machine includes a base 1 and a pair of relatively spaced substantially U-shaped frame members 2, each presenting a horizontal portion 3 and a pair of vertical portions or standards 4, attached at their lower ends to the base 1 and rigidly sustained thereon by diagonal braces 5, formed by suitably-bending portions of complementary strap-metal members which are employed in the production of the frame mem-

bers 2 and which in the formation of the horizontal portions 3 are spaced relatively to present slots or guideways 6, running through the entire length of the horizontal portions of the members. The main frame also includes a plurality, preferably four, of longitudinally-extending channel-iron members or bars 7, arranged in parallel relation and adjustably secured to the frame members 2 by means of fastening members or bolts 8, arranged in the guideways 6 and entered through the longitudinal slots 9, formed adjacent the ends of the bars 7, a pair of which are disposed in co-operative relation at the transverse center of the frame.

Resting on the frame members 2 and 7 as a base is a mold or box 10, divided into a pair of compartments 11 by means of a central vertical partition 12, clamped at its lower edge between the central pair of bars 7 and comprising side walls 13, end walls 14, and bottom boards or palette 15, the latter being provided with perforations 16 for the accommodation of main cores 17 and with perforations 18 to receive auxiliary cores 19, while the end walls 14 are provided on their inner faces with end cores 20.

The sides 13 are adjustably and pivotally sustained on the frame by means of strap-hinges 21, pivoted at their normally lower ends in bearing members 22 in the form of clip-bolts engaged with the horizontal portions 3 and entered through the guideways 6 thereof, while the end walls 14 are correspondingly secured on the frame by hinges 21, the bearing members 22 of which are entered through the longitudinal slots 9 in the frame-bars 7 and for movement longitudinally of the latter for obtaining a relative adjustment of the end walls toward and from each other, a similar adjustment of the side walls 13 being obtainable owing to arrangement of the clips 22 in the guides 6.

Disposed for vertical movement beneath the mold is a core-supporting frame comprising a pair of transversely-disposed pieces or bars 23, disposed, respectively, adjacent the frame members 2, and a plurality of longitudinally-extending pieces or bars 24, disposed in parallel relation and arranged in co-operative pairs, as shown, the bars 24 being connected in pairs by means of transverse bolts 25 and fixed to the bars 23 by means of clip-bolts 26, engaged with the latter bars

and with the bolts 25, as seen more clearly in Fig. 9, it being apparent that the pairs of bars 24 may be adjusted relatively toward and from each other in a direction longitudinally of the bars 23 through the medium of the clip-bolts 26.

Fixed on the ends of bars 23 are vertically uprising portions or arms 27, to the upper ends of which are pivoted links 29, in turn pivoted at their upper ends to brackets 30, fixed on the side walls 13 of the mold, similar brackets being fixed to the end walls 14 for pivotal engagement by the adjacent ends of links 29, in turn pivoted at their outer ends to vertical portions or arms 31, attached to the longitudinal bars 24, the arms 31 being adjustably secured in place on the bars by means of clip-bolts 32, entered through cross-pieces 33, provided at the lower ends of the arms and to bear beneath the edges of the bars 24, attention being directed to the fact that the arms 27 and 31 are slotted longitudinally at 34 for the reception of the pintles at the adjacent ends of the links 29, whereby a shifting pivotal connection is provided between the links and arms.

Extended transversely of the frame at points vertically beneath the bars 23 and journaled in bearings 35 on the vertical portions 30 of the frame members is a pair of relatively spaced operation-shafts 36, one of which is provided at one end with an operating-lever 37, these shafts being connected for uniform movement by a sprocket-chain belt 38, arranged on sprocket-wheels 39, fixed on the ends of the shafts, there being also fixed on each of said shafts a crank-arm 38', pivoted at its outer end in a U-shaped bearing member or clip 40, fixed on and adjacent the normally lower end of a connecting rod or link 41, which in turn is pivoted at its upper end to an arm or link 42, fixed on the adjacent bar 23, it being noted that the rod 41 normally projects slightly below the clip 40 for contact with one edge of the crank-arm 38', thus to lock the latter against movement in one direction, which will limit the upward movement of the core-frame, while the downward movement of the latter is limited owing to contact of the connecting-rod 41 with the other side of the arm 38', as seen in Fig. 2.

The cores 17 and 18 are secured at their lower ends between the pairs of bars 24 by means of bolts 43, whereby the cores will move with the core-frame for projection through the openings 16 and 18 into the mold or for retraction from the latter simultaneously with the movement of the side and end walls to open position, as seen in Fig. 2.

In practice when the parts are adjusted as in Fig. 1 the side and end walls of the mold will be maintained securely in active position and with the cores projected into the mold, thus adapting the device for the formation of hollow building-blocks. The mold

is filled with cement or other plastic material, which is rammed with tamping-mauls, the upper side of the block is troweled off smooth and immediately after this the lever 37 is swung to the position illustrated in Fig. 2, thus rotating the shafts 36, which serve through the medium of their connections with the core-frame to draw the latter vertically downward for withdrawing the cores from the mold and at the same time swinging the side and end walls by means of the links 29 to open position, whereupon the palette 15 with the blocks in position thereon may be readily removed to the drying-house. It is to be observed that owing to the clips 22 being movable in the guides 6 and 9 and the arms 27 and 31 attached for adjustment longitudinally of the bars 23 and 24 these parts may be adjusted for accommodating side and end walls of varying sizes, thus permitting ready change of the mold to produce different-size blocks. Bars 24 are, through the medium of the connection shown in Fig. 9, susceptible of adjustment transversely for properly centering the cores to accord with molds of varying sizes, it being understood, of course, that when the size of the mold is changed a palette or palettes of corresponding size will be employed therein.

From the foregoing it is apparent that I produce a comparatively simple inexpensive device which is admirably adapted for the attainment of the ends in view and one wherein the parts are susceptible of all necessary adjustments for varying the size of the mold, it being understood that in attaining these ends minor changes in the details herein set forth may be resorted to without departing from the spirit of the invention.

Having thus fully described my invention, what I claim is—

1. In a building-block machine, a frame having transversely-extending horizontal portions provided with longitudinal guide-slots, a plurality of longitudinal frame-bars having longitudinal slots, fastening devices entered through the slots in bars and horizontal portions for adjustably connecting the former with the latter, a pair of said bars being arranged in co-operative relation adjacent the transverse center of the frame, a mold sustained by the latter and comprising side and end walls, a partition clamped at its lower edge between the said pair of bars and dividing the mold into a pair of compartments, hinged members pivotally connected respectively with the horizontal portions and longitudinal bars of the frame and pivoted to the mold-walls, said walls being adapted to swing in a vertical plane to open or closed position, a vertically-movable core-frame, cores carried thereby for movement into and out of the mold, operative connections between the core-frame and mold-walls for moving the latter, and means for operating the core- 125

frame for simultaneously moving the cores and mold-walls to and from active position.

2. In a building-block machine, a frame having transversely-extending horizontal portions provided with longitudinal guide-slots, a plurality of longitudinal frame-bars having longitudinal slots, fastening devices entered through the slots in the bars and those in the horizontal portions for adjustably connecting the former with the latter, a pair of said bars being arranged in co-operative relation adjacent the transverse center of the frame, a mold sustained by the latter and comprising side and end walls, a partition clamped at its lower edge between the central pair of bars and dividing the mold into a pair of compartments, bearing members adjustably arranged in a transversely- and longitudinally extending slot, hinged members pivotally connected with said bearing members and engaged respectively with the side and end walls to permit the latter to swing in a vertical plane to open or closed position, said bearing members being adjustable in their respective slots for permitting adjustment of the mold-walls in pairs toward and from each other, a vertically-movable core-frame, cores carried thereby for movement into and out of the mold, connections between the core-frame and mold-walls for moving the latter, and means for operating the core-frame to simultaneously move the cores and walls to and from active position.

In testimony whereof I affix my signature in presence of two witnesses.

SAMUEL A. LATIMER.
